removing portions of the foil about them, such as 17 and 18, to provide a suitable border strip, 19, and blocks, 20, of foil, which is the first step in 5 making the letters. These blocks are located in the position which it is desired that the letters assume. By further operations, portions such as 21 and 22 of these blocks 20 are removed to provide letters, 23, together with the completed marginal border, 24. The letters are in reverse on 10 the back of the plates, as indicated in Fig. 5, that they may properly read from the opposite side.

We then coat the inner back surface of the front plate with a waterproof paint, 25, such as indicated in Fig. 6, covering the portions of 15 the plate from which the foil has been removed as well as covering the foil. If it is desired that the letters of the foil shall form the finished sign, we may leave this foil in the position as illustrated in Fig. 6 with the backing thereover to 20 protect them and then mount the sign in any suitable frame, in which case the sign will not be translucent. Usually, however, we desire to provide a transparent portion forming the letters and thus remove, as at 26, the foil 23, which forms 25 the letters, which removing also takes the coating, 27, on this foil, thus leaving the transparent portions 28, in sharp contrast to the background 25, along the shape of the letters and also along the margin 29, about the front plate.

If, however, it is desired to have a black letter 30 and a transparent background, we will cause the foil to cover the background and paint over the letters the portions from which the foil is removed and then remove the foil.

Also, should it be desired to provide a color 35 where the glass is transparent a suitable colored paint may be applied thereto in which case the transparency will be destroyed and the translucency diminished.

After providing the front plate in this manner, 40 a strip of tape 30, is placed along the marginal back edge of the plate and a backing plate 31, which is frequently a white plate of translucent character, such as opal glass, is positioned against 45 the marginal spacing tape and a strip of tape 32 is positioned about the edges of the assembly so as to bridge both edges of the plates and the spacing tape 30 and extend along the outer surfaces of the plates to prevent the entrance of 50 moisture as at 33.

This translucent opal glass provides a white surface to contrast with the waterproof coating, which is often desirably black, permitting a very

handsome sign to be formed by reason of the white showing thru the transparent cutout portion, such as at 28-29, and surrounded by a coating of black. Further, this translucent back plate permits the transmission of light therethru to be 5 observed thru the transparent characters 28 and 29, enabling the sign to be used in the dark or in a subdued light.

A frame is provided for this assembly consisting of angle or channel shaped strips of metal 10 34 and 35, with their upper L-shaped portions overlapping and secured to a wooden or non-metallic strip 36, by means of a screw 37, which will be adjustable as to the thickness and extend about the sign to be soldered at the mitered corners 39 to secure the same in position.

By the arrangement of the spacer 30, an air pocket 40 is provided which prevents sweating between the glasses and also an accumulation of moisture, which may spot the coating on the back 20 of the front plate, thus we provide a sign which will outlast any sign in which the plates touch each other or the back plate touches the coating on the front plate.

Further, as this spacing strip 30 is of soft tape 25 material, a cushion-like effect is provided between the plates to prevent their breaking or cracking from jars or strong impacts received upon the outer surface of the plates and which also permits expansion and contraction of the 30 parts due to changes in temperatures.

The foregoing description is directed towards the method and construction illustrated, but we desire it to be understood that we reserve the privilege of resorting to all the equivalent changes 35 to which the construction and method are susceptible, the invention being defined and limited only by the terms of the appended claim.

We claim:

A sign comprising a transparent front plate, a 40 coating on a part of the plate leaving other parts uncoated, whereby to provide characters of the desired shape, a translucent plate back of said front plate, a strip of tape along the marginal edges of said plates and located between them and 45 providing an air space between the plates, an additional piece of tape bridging the tape between the plates and overlapping on the front and back surfaces of both of said plates and a frame about the edges of the plate whereby the plates are held 50 together.
